UNITED STATES PATENT OFFICE

JOHN D. BURKHOLDER, OF HARRISONBURG, VIRGINIA, ASSIGNOR TO AUTOMATIC DEVICES, INC., OF HARRISONBURG, VIRGINIA, A CORPORATION OF VIRGINIA

SWITCH

Application filed February 6, 1928. Serial No. 252,311.

This invention is directed to an improvement in electric switches designed for controlling the flow of electric current for the generation of heat.

- 5 The switch is designed primarily for, though in nowise limited to, the control of the current for the generation of heat in certain therapeutic devices, such for example as a blanket designed for general application 10 to the body and a pad or pads constructed for application to particular parts of the body. In this use, the switch is designed to provide a means whereby the degree of heat may be selectively controlled, the application of the 15 current to the blanket or to the blanket and pad may be selectively controlled, and the switch may be automatically disconnected or opened following a predetermined degree of heat in either the blanket or pad.
- 20 The switch is constructed for selective manual setting and for manual or automatic disconnection or breaking to thereby provide for the control of the heating current at the will of the user, or automatically independently of the will of the user in the event a 25 predetermined heat is reached in the therapeutic appliance.

The switch is designed to include an element providing an audible signal when the 30 switch is closed and the current is flowing.

The invention is illustrated in the accompanying drawings, in which:

Figure 1 is a top plan view of the improved switch, the casing being in section and a plurality of therapeutic elements being shown in outline.

Figure 2 is a bottom plan of the switch.

Figure 3 is an edge view of the switch.

Figure 4 is a plan of the switch casing.

40 Figure 5 is a detail showing the contact strip controlling buttons.

Figure 6 is a diagrammatic view showing a modification of the automatic release for the spring contact strips.

45 Figure 7 is a diagrammatic view showing a modified form of automatic release circuit.

Figure 8 is an enlarged detail showing the parts of the modified form of automatic release in released position.

50 The switch proper, which forms the sub-

ject-matter of the present application, comprises an insulating block or base 1 on the upper side of which are arranged two spring contact strips 2 and 3. These contact strips, which are in the form of elongated strips of 55 spring metal, are secured to one end of the base through the medium of downturned flanges 4 and 5 on the respective strips fixed to the base by screws 6. A conductor plate 7 is secured to the surface of the switch base 60 and in electrical circuit through contact with the spring strip 3.

The connected terminal of strip 2 is, 65 through the medium of the screws 6, electrically united to a plate 8 which overlies and rests upon the upper surface of the base, providing a conductor terminal 9. The contact strip 3 is similarly electrically united to conductor plate 7. A conductor strip 10 is secured to the upper surface of the base and 70 extends longitudinally thereof to a point adjacent the free ends of the contact strips 2 and 3, where the conductor strip is provided with a right angled portion 11 which underlies the free ends of the strips 2 and 3 and is normally 75 slightly spaced from the base.

The portion 11 of the conductor strip carries a contact point 12 underlying the contact strip 2 and contact point 13 underlying the contact strip 3, the relation of the parts 80 being such that when the contact strip 3 is depressed, a contact on such strip will engage the contact 13 and depress the contact point 12 by moving the conductor strip 10 and right angled portion 11.

85 A conductor terminal 14 is secured to and in electrical connection with the conductor strip 10 adjacent its fixed end. A terminal connector strip 15 is secured on the base beneath the free ends of the contact strips 2 and 3, this terminal connector strip being preferably of right angled form with a portion 16 underlying the contact strips 2 and 3 and a portion 17 extending longitudinally of the base and in electrical connection with 90 a conductor terminal 18 to which the outgoing service wire is directly connected.

95 The portion 16 of the terminal connector strip is provided with contact points 19 and 20, the former underlying a contact point 21 100

on the under side of contact strip 2 and the latter underlying a contact point 22 on contact strip 3. The contact strip 2 is provided with a further contact point 23 to cooperate with the contact point 12 on the portion 11 of the conductor strip 10, and the contact strip 3 has an additional contact point 23' to engage contact point 13 on portion 11 of conductor strip 10.

10 Thus, when the contact strip 2 is depressed, contact point 21 thereon will engage contact point 19 on the terminal connector strip 15 and contact point 23 on such strip 2 will engage contact point 12 on conductor strip 10. 15 When contact strip 3 is depressed, point 22 thereon will engage contact point 20 on the terminal connector strip 15 and at the same time contact 23' will engage the contact 13 of the conductor strip 10 and depress said strip to move the contact point 12 out of possibility of engagement with contact point 23 on strip 2.

Means are provided whereby either or both the contact strips 2 or 3 may be held in operative position against their inherent spring tendency. This means includes duplicate latches 24 and 25, one for each contact strip and each comprising upright portions 26 pivotally supported on the ends of the base, as at 27, the upper ends of the upright portions being formed as hooks 28 beneath which the extreme ends of the contact strips are adapted to engage when the strips are depressed, the upright portions above the hooks being outwardly flared, as at 29, to insure the strips riding beneath the hooks in the operation of the parts. The lower ends of the upright portions of the latches are extended beneath the base as tails 30, which tails diverge from the base and are normally held to maintain the hooks in operative relation by springs 31 arranged between the tails and base.

An automatic trip element 32 is secured on the under surface of the base, it being in the form of a thermostat involving a conventional construction, as of strips of different coefficients of expansion. The free end of the element has an upstanding flange 33 to which is secured a strip of non-conducting material 34 which directly underlies the tails 30 of both latches 24 and 25. The strips making up the trip element are arranged to compel upward movement of the free end of the element when heated to a predetermined degree, so that the portion of the trip element through application of the current will actuate the latches to release the contact strips 2 and 3 or either of them when in operative position.

60 A main conductor terminal 35 is secured to the under side of the base and a conductor 36 leads therefrom to a coil 37 and from the latter to a conductor terminal 38. A spring strip 39 is secured to the under side of the base, having its free end overlying the core

of the coil 37, so that in the passage of the current there is a slight vibration of the spring strip and an audible signal incident to the contact of the strip with the core of the coil, thus providing the audible feature of the 70 switch.

The trip element, or more particularly the plates making up such element, are heated through the medium of a conductor 40 coiled about the plates, such conductor having one terminal 41a connected to the terminal 14 on the conductor strip 10 and the other terminal indicated at 41, leading to the therapeutic appliance or other control device, as will later appear.

80 The use of the switch will be described in connection with the control of the heating of therapeutic appliances, such as a blanket and pad, though of course it is obvious that the switch is adapted for the control of current for other uses.

The blanket is shown at 42 and the pad at 43. The detailed structure of these parts is not important in the present application, except that the blanket contains an electric 90 conductor 44 adapted to heat the blanket in the passage of current therethrough and the pad contains a conductor 45 for the heating of the pad in the passage of the current. The blanket and pad conductors are shown in series and connected by a conductor 46 leading to the incoming main conductor terminal 38 on the switch to which terminal the incoming service conductor 47 is connected by terminal 35 and conductor 36 through coil 100 37.

The other terminal of the series conductor 44, 45 of the blanket and pad is connected by a conductor 48 to the terminal 9 on the switch, that is, to the contact strip 2. A conductor 49 leads from conductor terminal plate 7 on the switch to the blanket conductor 44 beyond the pad. As the conductor terminal plate 7 is part of strip 3, it is apparent that this strip 3 is therefore in circuit with the 110 blanket to the exclusion of the pad.

At an appropriate point in the conductor 44 of the blanket, there is arranged a thermostat involving blades of strips of different coefficients of expansion, one blade as 50 being in circuit with the conductor 44 and the other blade as 51 being in circuit with the conductor 41 leading to the conductor 40 coiled about the trip 32. A similar thermostat is arranged in the conductor 45 of the pad, the blades 52 and 53 of the latter thermostat, however, being connected to the conductor 45 at the entrance point and exit point of the pad.

These thermostats are substantially identical in structure and will be referred to as reverse blade thermostats in that the blade terminals are normally spaced and are brought into engagement in response to a predetermined degree of heat. The closing 125 130

of the thermostatic blades serves to cut off the current, obviously in the case of the pad shunting the current entirely from the pad and in the case of the blanket operating the 5 trip for the latches to release the contact strips 2 and 3.

The switch as an entirety is designed to be secured within a cylindrical casing made up of sections 54 and 55 having their mating 10 ends adapted for threaded connection to provide for convenient separation when desired. The base 1 is secured in the section 54 by screws 56, and this section 54 is provided with two push-buttons 57 and 58 which extend 15 through guides 59 in the casing and cooperate respectively with the free ends of contact strips 2 and 3; that is, the push-buttons overlie the free ends of the strips so that either strip may be operated into locking cooperation 20 with its latch by depression of the particular button. The buttons are preferably constructed so that they may be readily distinguished by the sense of touch, for example, button 57 may have a pointed end 25 while button 58 has a flat or rounded end.

A trip button 60 is connected to the trip element 32 and extends through the section 30 54 of the switch casing, permitting the trip to be operated manually at will. One end of the casing section 54 may be formed in any appropriate manner for the passage therethrough of the main conductors 47 and 35 61, the latter being the outgoing main conductor and being connected to the conductor terminal 18 on the connector strip 15 of the switch.

The remaining section 55 of the switch 40 casing may be terminally formed for the passage therethrough of conductors 41, 46, 48 and 49. The switch as a whole is thus arranged in the terminal cord which of course is adapted to be connected to any plug or light socket by an appropriate connector at the ends of the conductors 47 and 61.

45 Assuming the parts in the normal position indicated in the drawings and it being desired to heat the blanket and pad, push-button 57 on the switch is operated, depressing contact strip 2 and causing it to be held in depressed position by its latch 24. When this contact strip is depressed, contact points 21 and 23 thereon engage contact points 19 and 12 respectively. The current will now flow through the incoming conductor 47 to terminal 35, thence to the audible signal through conductor 36 and through a conductor 62 connected to the terminal 38 on the switch and serving as the incoming conductor to the pad and blanket in series. From the blanket, 50 the current passes over a conductor 48 to terminal 9 on the switch through the contact strip 2, contact points 21 on strip 2 and 19 on connector strip 15 and thence through conductor 18 on the strip 15 and through the 55 outgoing service conductor 61. This connec-

tion may be broken manually at will by operation of the trip button 60 and corresponding action of the trip element 32 to actuate the latch 24 to release the contact strip 2.

If, during the heating of the therapeutic 70 appliance, the pad heats to a predetermined point, it will be cut out or shunted by the action of the thermostatic element including the blades 52 and 53. If the blanket heats to a predetermined point, the thermostatic element including the blades 50 and 51 is 75 actuated by the heat and the current directed to conductor 41 to heat the trip element 32, passing beyond the coil of the trip element to terminal 14 on the conductor strip 10, through said strip 10 to contact point 12, thence through contact point 23 on strip 2 to and through contacts 21 and 19, thence 80 through connector strip 15, terminal 18 and outgoing service conductor 61. As the thermostatic trip element 32 is heated by the current in the coil, it is automatically operated to exert pressure upon the tail 30 of latch 24 to release strip 2, breaking the continuity of current to the blanket.

If the blanket alone is to be heated, push-button 58 is operated, depressing contact strip 3. The current then flows through the blanket and back to the switch through conductor 49 to the plate 7, to conductor strip 3, through the contact points 22 and 20, connector strip 15, conductor terminal 18 and outgoing service conductor 61. The automatic release of this contact strip 3 occurs in the identical manner described in connection with the contact strip 2.

In Figures 6 and 8 there is illustrated a modified form of automatic release of the spring strips. In this modification, the 105 spring strips, here indicated at 63 and capable of being operated by push-buttons 64 as in the preferred form, are designed to be engaged and held in contact or closed relation by a hook 65 pivotally supported at 66 and having a depending arm 67. When in latching position, the hook bill overlies the end of the spring strip, the pivot 66 of the hook latch being on a plane above the strip when the latter is in locked position.

A trip element 68 is arranged below the base plate of the switch, this plate being substantially in L-form pivotally mounted at 69 near its upper end and formed with a lateral terminal 70 adapted to bear against the extreme lower end of the arm 67 of the hook latch. The trip member 68 extends past and serves as an armature for an electro-magnet 71, being projected below and beyond the magnet and provided with a spring 72 and bearing between the free end of the trip element 68 and the base.

In operative position, the bill of the hook overlies the spring strip 63, maintaining the latter in contact position, and the extreme end of the arm 67 of the hook latch rests in

front of the upper lateral end 70 of the trip member 68. The spring 72 is of sufficient strength to prevent the upward pressure of the spring strip 63 from moving the trip member.

5 When the electro-magnet 71 is energized, as by the closing of the thermostat 73 in the blanket, the trip member is attracted causing its lateral end 70 to move outwardly, that is, toward the right in Figure 6. In this movement, the free end of the lateral portion 70 of the trip member displaces the lower end of the arm 67 of the hook latch, finally freeing the latch and permitting the upward stress of the spring strip 63 to swing the hook latch on its pivot 66 to free said spring strip 63.

10 The parts are then in the positions indicated in Figure 8. Upon deenergization of the electro-magnet, which of course follows the deenergization of the blanket by the release of the spring strip 63, the spring 72 tends to return the contact member to normal position while the hook latch 67 will rest on top of 70. As either spring strip is moved 15 to contact position, the bill of the hook is displaced and rides over 70 into position shown in Figure 6, being prevented, however, from moving to a position to release the spring strip by engagement of the free end of the arm 67 with the lateral portion 70 of the trip member 68. A push-button 74 is arranged 20 beneath the trip member 68 to provide for manual operation of the same in a manner similar to the result of the energization of the electro-magnet. Thus, the spring strips 25 may be released manually if desired in order to control the flow of current to the blanket either manually or automatically as described in connection with the preferred 30 form.

35 In Figure 7, I have illustrated a slightly modified form of current means for the operation of the release thermostat. In the preferred form, a portion of the conductor of the blanket is utilized to take care of the current amperage during the current cut-off operation. In order to avoid this use of a portion of the conductor of the blanket, the 40 blanket control thermostat indicated in Figure 7 at 75 and corresponding to the thermostat 50, 51 of the preferred form is arranged in an independent circuit having a resistance wire 76 of sufficient length and capacity to take care of the current shunted there- 45 through in the closing of the thermostat. Otherwise the operation of this automatic release is as in the preferred form and the parts shown in Figure 7, being similar to those in the preferred form, are given cor- 50 responding reference characters in order that the construction of this modified form 55 may be understood.

60 What I claim to be new is:

65 1. In a switch for controlling the ener-

gization of a therapeutic appliance, a plurality of spring strips for selective energization of the appliance, locking members for holding the spring strips in contact position, a thermostat to operate the locking members to release the spring strips, and means responsive to heat conditions of the appliance for energizing the thermostat. 70

2. In a switch for controlling the energization of a therapeutic appliance, a plurality of spring strips for selective energization of the appliance, locking members for holding the spring strips in contact position, a thermostat to operate the locking members to release the spring strips, means responsive to heat conditions of the appliance for energizing the thermostat, and a push-button for operating the thermostat at will to release the locking means. 75

3. A switch for controlling the selective energization of a therapeutic appliance, comprising independent spring contact strips for controlling the current in accordance with the selected energization, a locking lever pivotally mounted adjacent the free end of each strip and formed to engage and hold the strip in contact position, manually operable means for moving the selected strip within the influence of the locking lever, and a single thermostat responsive to heat conditions of the appliance to cooperate with both levers 80 for releasing the set strips. 90

4. A switch for controlling the selective energization of a therapeutic appliance, comprising independent spring contact strips for controlling the current in accordance with the selected energization, a locking lever pivotally mounted adjacent the free end of each strip and formed to engage and hold the strip in contact position, manually operable means for moving the selected strip within the influence of the locking lever, a single thermostat responsive to heat conditions of the appliance to cooperate with both levers 95 for releasing the set strips, and a push-button 100 for operating the thermostat without regard to the heat conditions of the appliance. 105

5. A switch for controlling the selective energization of a therapeutic appliance, comprising independent spring contact strips for controlling the current in accordance with the selected energization, a locking lever pivotally mounted adjacent the free end of each strip and formed to engage and hold the strip in contact position, manually operable means for moving the selected strip within the influence of the locking lever, a single thermostat responsive to heat conditions of the appliance to cooperate with both levers 110 for releasing the set strips, and a push-button for operating the thermostat without regard to the heat conditions of the appliance. 115

6. A switch for controlling the selective energization of a therapeutic appliance, including a spring strip adapted when in contact position to energize the appliance for a 120 125 alarm included in the circuit. 130

particular heat condition, a second spring strip adapted when in contact position to hold the energization of the therapeutic appliance for another heat condition, a latch adapted to automatically engage and hold each spring strip in contact position, independent means whereby the respective spring strips may be moved to contact position, and a latch releasing thermostat responsive to particular heat conditions in the appliance for releasing the set latches to free the strips.

7. A switch for controlling the selective energization of a therapeutic appliance, including a spring strip adapted when in contact position to energize the appliance for a particular heat condition, a second spring strip adapted when in contact position to hold the energization of the therapeutic appliance for another heat condition, a latch adapted to automatically engage and hold each spring strip in contact position, independent means whereby the respective spring strips may be moved to contact position, a latch releasing thermostat responsive to particular heat conditions in the appliance for releasing the set latches to free the strips, and a push-button for manually operating the thermostat independent of heat conditions in the appliance.

26 In testimony whereof I affix my signature.

JOHN D. BURKHOLDER.
